UNITED STATES PATENT OFFICE.

JOHN R. KIEL, OF YOUNGSTOWN, OHIO.

DOOR FASTENER.

Application filed April 1, 1922. Serial No. 548,804.

To all whom it may concern:

Be it known that JOHN R. KIEL, citizen of the United States of America, residing at Youngstown, in the county of Mahoning and State of Ohio, has invented certain new and useful Improvements in Door Fasteners, of which the following is a specification.

This invention relates to door fasteners, and more especially for doors for garages, barns, and the like, where it is desired to swing the doors outwardly at approximately 90° from the position when closed. The principal object of my invention is to provide a door fastener which will securely hold the door in a set position, and which may be easily manipulated.

Another object is to provide means for adjusting the device so that the fastener will hold the door at a degree less or greater than 90° from the position when closed.

The drawing illustrates the preferred embodiment of the invention. However, it is to be understood that in adapting the same to meeting different conditions, various changes in the form, and minor details of construction, may be resorted to without departing from the nature of the invention, as claimed and set forth in the drawing.

Figure 1 is a front elevation of a portion of a door-way, with a door secured thereto, and showing the device in a position which secures the door when open.

Figure 2 is a sectional view of Figure 1 taken on line 2—2, which shows a top plan view of the door fastener installed, securing the door in an open position.

Figure 3 is a detail view of the device showing a securing member.

Figure 4 is a side view of Figure 3.

Figure 5 is a detail view partly in section showing the automatic stop shown in Figures 3 and 4.

By referring to Figure 1 it will be seen that I have shown a side wall 1 of a building provided with a door jamb 2. To this door jamb 2 there is secured a door 3 held by means of hinges 4.

By referring to Figures 1 and 2 it will be seen that my door fastener is attached to a door in an open position, or in a position approximately 90 degrees from the position when closed.

Attached to the door jamb 2, I have provided a bracket 5 having an outturned arm

6. To this outturned arm 6 there is secured a holding arm 7 by means of a bolt 8 passing through the arm 6 in such a manner that the bolt 8 forms a pivot for the holding arm 7.

By referring to Figure 2 it will be seen the holding arms 7 is provided with an in-turned curved end 9 having a plurality of holes 10 in order to adjust the range of the swing of the door to meet requirements for fastening the door. The holding arm 7 is provided with an outer end 11, carrying a slideable pin 12 which slides in the slot 13 of a bracket 14, which is attached to the door 3, at point 15, so that when the door is in an opened position the slideable pin 12 is at the inner end 16 of the slot 13. When the door is in the position as shown in Figures 1 and 2, or open, the door may be secured by swinging downwardly into a vertical position, a securing arm 17 which is pivotally attached to a bracket 18 by means of a pivot pin 19. When the securing arm 17 is placed in this vertical position, the end 20 comes in close contact at point 21 of the holding arm 7. This holding arm 7 is preferably made of an angle iron having the outer portion of the same in a vertical position so that the end 20 of the securing arm 17 finds a parallel plane for engagement.

In order to keep the holding arm 7 from a tendency to turn or twist when in close engagement with the end 20 above mentioned, I have provided a reinforcing member 22 secured within the angle of the holding arm 7 at point 21 of the holding arm 7.

When it is desired to release the door so that the same may be closed, the operator swings the securing arm 17 to the right in order that said securing arm 17 may take a position as to be directly over the bracket 18 and in a horizontal position. In order that the securing arm 17 may remain in this position until desired for securing the door when opened, I have provided a spring controlled latch member 23 which functions with an opening 24 formed in the bracket 18.

What I claim is:

In a device of the class described, a holding arm pivotally mounted to a bracket attached to a door jamb, the inner end of said holding arm being inwardly curved and provided with a plurality of holes for adjusting, an outer end of said holding arm pro-

vided with a slidable pin secured thereto, a bracket secured to a door having a horizontal slot formed therein for the reception of above mentioned slidable pin, a bracket secured to the door directly underneath said holding arm, a securing arm pivotally attached thereto, means for holding said securing arm in a horizontal position when

not in position for fastening door, substantially as described for the purpose set forth. ¹⁰

In testimony whereof I affix my signature.

JOHN R. KIEL.
